Leonard Kennedy and Donald C. Kennedy,
Dayton, Ohio

Application August 30, 1952, Serial No. 21,273

Term of patent 7 years

(Cl. D1—2)

To all whom it may concern:

Be it known that we, Leonard Kennedy and Donald C. Kennedy, citizens of the United States, residing at Dayton, in the county of Montgomery and State of Ohio, have invented a new, original, and ornamental Design for an Advertising Unit for Clothes Driers, of which the following is a specification, reference being had to the accompanying drawing, forming a part thereof, wherein:

Figure 1 is a perspective view of an advertising unit for clothes driers, showing our new design;

Figure 2 is a plan view of the unit; and

Figure 3 shows the end elevational view.

We claim:

The ornamental design for an advertising unit for clothes driers, substantially as shown.

LEONARD KENNEDY.
DONALD C. KENNEDY.
